Fig.6.

FIG. 1 is a perspective view of a portable phonograph in a partially open position, embodying my new design;

FIG. 2 is a rear elevational view of the portable phonograph in a closed position;

FIG. 3 is a side elevational view thereof, the side not shown being a mirror image of the side shown;

FIG. 4 is a front elevational view thereof on a reduced scale;

FIG. 5 is a bottom view thereof on an enlarged scale;

FIG. 6 is a front perspective view thereof on an enlarged scale, the rear perspective view not shown being a mirror image of the front perspective view shown, with the exception of the three small projections shown in FIG. 2.

The dominant features of my design reside in those portions shown in full lines on the drawing.

I claim:

The ornamental design for a portable phonograph, as shown and described.
